GRAVITY OPERATING DEVICE FOR SORT-
ING FRUITS OR VEGETABLES

George J. Olney, Westerville, N. Y.

Application November 7, 1932, Serial No. 641,563

10 Claims. (Cl. 209—173)

My present invention relates to a machine for sorting or cleaning fruit or vegetables which machine operates upon the floatation principle, that is, the machine uses a liquid in which the material to be cleaned or sorted is separated according to the differing gravity of the good material and the waste or poor material relative to the gravity of the liquid or sorted according to the different gravity of two grades of good material.

10. This invention is a further development of, and improvement upon my invention in a somewhat similar machine shown in my co-pending application Serial No. 522,349 filed March 13, 1931 upon which a patent was issued February 28, 1933, No. 1,899,632.

15. The purpose of this invention is to provide a new and improved machine of the type mentioned and particularly to provide a machine in which the sorting operation is performed or completed much faster, say in from one and one-half to six seconds as against a period heretofore lasting up to twenty seconds, such reduced time of separation effecting a more accurate and positive separation in that the lighter or waste materials or poor material does not have time to become saturated with the liquid and so be passed by the machine as good material instead of waste material or be passed with the wrong grade when two good grades are being separated.

20. Another advantage of so speeding up the period of separation is that the machine can be stopped much quicker after the operator ceases to feed new materials to the machine.

25. Another object of this invention is to provide a machine of such arrangement and combination of its parts and of such arrangement of the feeding of material and the feeding of the liquid into the machine and the passing of the liquid out of the machine as to prevent the formation of any current or currents of liquid which will interfere or prevent the quick and accurate separation of the fruit or vegetable being separated.

Still further purposes of this machine are as follows: To provide means for depositing the material to be sorted and its accompanying liquid upon the surface of the separating zone gently enough to allow floatation separation to begin immediately and without causing an interfering current of liquid in the separating zone; to continuously spread the incoming material in a constantly moving line over an annular separating zone; to have the skimming means follow said delivery means at a determined but adjustable distance and to have said skimming means extend over the same zone as the de-

livering means cover; to provide convenient and accurate means for timing the interval between delivery and the arrival of the skimming means to any given portion of material and to provide means for accurately adjusting such interval of time; to provide convenient and accurate means for adjusting the depth of the skimming mechanism relative to the level of the liquid; and further to feed into the machine sufficient liquid to carry on the two discharge operations, that is of good heavy material and poor light material, but to feed the incoming liquid into the machine at different places and in such a manner as to provide currents of liquid for the outgoing material, but to prevent the formation of a current in the separating zone; to form the chutes distributing the material and some liquid to the separating zone so that such material and liquid will be distributed evenly and regularly and in a thin layer over the width of the separating zone; to so shape and combine the fixed spout leading to the central hopper having the said chutes so that the portions of the said hopper leading to the different chutes will receive an equal amount of material and liquid and will pass such material on to the said chutes in an even, regular and continuous manner.

Fig. 1 is a vertical longitudinal sectional view through a machine embodying this invention mostly on line 1—1 of Fig. 2.

Fig. 2 is a horizontal sectional view of said machine mostly on line 2—2 of Fig. 1.

Fig. 3 is a view similar to Fig. 1 of the distributing chutes, its open-topped hopper, the two depending flanges which limit the separating zone, the funnel located within the inner flange and the vertical shaft which carries at its lower end the foregoing parts.

Fig. 4 is a rear view on a considerably enlarged scale of one end of the delivery chute and adjacent parts of the machine approximately on line 4—4 of Fig. 7.

Fig. 5 is a view mostly in side elevation of the outer end of a delivery chute as seen on line 5—5 of Fig. 4.

Fig. 6 is a top plan and sectional view on line 6—6 of Fig. 3 of the zone-forming flanges, the funnel within the inner flange and the skimmers between the flanges and the supporting parts therefor.

Fig. 7 is a top plan view of the hopper and distributing chutes and the supporting shaft in section separate from other parts of the machine.

Referring to the drawings in a more specific description it will be seen that the machine in-

cludes a suitable framework having upright standards 10 and cross bars 11, a large outer main tank 12 supported by said framework, an inner tank 13 fixed as by spacers 77 within the central portion of said larger tank, material feeding or delivery chutes 14 receiving the material and some liquid from a centrally-disposed open-topped hopper 15 attached to said chutes and a pair of flanges or collars, namely an outer 10 circular flange 16, a smaller-diaetered concentric flange 17 and a funnel 18 occupying the space within said inner flange.

The outer main tank 12 is preferably formed so as to have its larger part in the form of an 15 inverted cone surmounted by a relatively short cylindrical portion. This is accomplished conveniently by having the larger portion of said tank 12 composed of an inwardly and downwardly sloping wall 19 surmounted at the top by a 20 short cylindrical vertical wall 20. At its bottom this tank is provided with an outlet port 21 opening into a return bend 22 the other end of which is connected to the upwardly and outwardly 25 slanting pipe 23. This pipe 23 extends upwardly just outside the sloping portion of the tank 12. Just below the water level 24 in the tank 12 the pipe 23 extends outwardly substantially in a horizontal line into the near end of a suitable revolving cylindrical screen 25 for separating the 30 good heavy material from the liquid. Extending tangentially into the return bend 22 more or less in line with the pipe 23 there is provided a pipe 26 adapted to feed liquid into said bend and up through said inclined pipe 23 and operating 35 more or less as an injector so as to produce a current of liquid from the bottom of the tank 12 out through its lower port 21 and up through said pipe 23.

The smaller tank 13 has its lower half formed 40 of an inwardly and downwardly slanting wall 27 forming an inverted cone preferably of substantially the same angle as the inverted cone of the lower part of the main tank, but fixedly spaced a short distance from said main tank so 45 as to provide a restricted passageway 34 between said two tanks leading downwardly to the port 21 at the bottom of the outer tank. The upper half of the said smaller tank has a cylindrical wall 28. From the upper edge of this cylindrical 50 portion there extends inwardly a top 29 which slants slightly downward as it extends inwardly. Towards its center, this top ceases but is connected to a downwardly extending sleeve 30 into which extends and rotatably fits the lower 55 tubular spout portion 31 of the funnel 18. A short distance below the lower end of the spout 31 the sleeve 30 is connected to a pipe 32 which extends radially outward on a slight downward slant through the wall 28 of the inner tank and 60 through the sloping wall 19 of the outer tank and ultimately into the receiving end of a suitable cylindrical rotating screen 33 adapted to separate the light or waste material from its carrying liquid. It will be seen that there is formed 65 between the upper part of the outer tank 12 and the upper part of the smaller inner tank 13 an annular chamber of considerable area at the top but of gradually reduced size as the chamber extends toward the passageway 34 formed between the lower parts of said two tanks and 70 leading to the outlet port 21.

The function of this inner tank is to set an inner bound to the annular chamber within the main or larger tank 12. The main chamber 75 within this inner tank in fact remains empty of

water or materials, but at the center of the inner tank and immediately below its top 29 and about the sleeve 30 there is formed a relatively small annular water collar or chamber 78 by means of an angularly shaped band 79 circular in form having its opposite edges attached respectively to the said top 29 and the sleeve 30. Several small spaced outlets 35 from this water collar are provided in the top wall thereof, viz: in the portion of the top 29 of the tank 13 that is above said water collar. The single inlet opening 36 into the small water collar 78 is preferably located on the vertical side of the band 79 and is connected to the inner tangentially arranged end of water pipe 37 which then extends through the empty main chamber of the inner tank and through the wall of said inner tank itself and through the passageway 34 and through the slanting wall 19 of the outer tank and then connects to the main liquid supply pipe 38 coming from the pump 39. It will be seen that the sleeve 30 and pipe 32 extending therefrom do not open into the chamber of the inner tank.

Mounted in upper and lower bearings 40 and 41 respectively secured to upper and lower cross bars 11 of the frame there is provided a power-driven vertical shaft 42. This shaft has its axis in line with the vertical axial center of said main tank and the smaller tank. Suitably secured near the lower end of said shaft is a hub 43 and thereabove is placed a rigid disk and supporting member 44. Above the disk there has been placed upon the said shaft the combined hopper and delivery chute member consisting of the two-chambered open-topped hopper 15 and the two outwardly extending chutes 14. The said disk 44 is provided with a series of closely spaced holes 45 extending in a circle about said disk in order to allow for the axial adjustment of the said delivery chutes 14 relative to the disk which is fixed 115 relative to the shaft 42 and the hub 43.

As it is necessary to adjust the shaft 42 vertically in order to adjust certain parts carried by the said shaft relative to the liquid level in the main tank, the worm gear 46 used to drive said 120 shaft 42 is secured to said shaft by a spline 47 engaging a keyway in said shaft whereby said worm gear may slide longitudinally of the shaft as the shaft is adjusted vertically relative to the bearings carrying said shaft and of course vertically relative to the tank. Such adjustment of the shaft is accomplished by the use of an adjusting nut 48 engaging said shaft above a false collar 49 immediately above the upper bearing 40.

Projecting rigidly outwardly from the hub 43 130 on the shaft 42 there are provided a plurality, say four, rotating arms 50 which extend outwardly immediately above the outer and inner flanges 16 and 17 and support said flanges as by the use of short vertically arranged fingers 51 135 depending from each arm and secured to the upper edges of said flanges. The outer flange 16 is spaced as close as practicable to the adjacent cylindrical portion 20 of the outer or main tank 12 and extends downwardly vertically but terminates short of the adjacent portion of the tank. The inner flange 17 is considerably deeper and extends down some distance past the upper edge of the inner tank 13 and is spaced some distance from the vertical wall of said inner tank. These 140 two flanges by setting down into the liquid establish or determine the separating zone 52 of the machine. Such separating zone is in the form of a ring extending about the main tank. Some distance down from the outer edge of the inner 145 tank 13 there is provided a flange 53 which is

flange 17 there is securely and imperforately attached the outer edge of the funnel 18. The main body of this funnel extends slantingly inwardly towards the axial center of the tanks and is there provided with the downwardly projecting spout 31 rotatably fitting into the sleeve 30 already mentioned as provided in the center of the inner tank 13.

The machine here described is arranged to have two oppositely arranged material delivery chutes 14. It will be understood, however, that this is simply a preferred and convenient form of assembling the machine and that obviously a machine may be built embodying the principle of my machine while provided with only one delivery chute 14. On the other hand with a sufficiently large machine and in a machine operating upon materials that can be separated in liquid very quickly, the number of these delivery chutes might be increased to three or even to four. A machine using two delivery chutes, however, is believed to be the preferred form as this provides a sufficiently large capacity for the machine and provides a sufficient range of space between each delivery chute 14 and its co-operating and following skimmer and still allows a positive and even division of the material and liquid between the two chutes as the material and liquid are delivered into the two-chambered hopper hereinafter described.

As the machine is illustrated, the shaft 42 and accordingly the parts suspended therefrom and including the chutes 14 and the skimmers 53 will rotate anticlockwise as seen in Figs. 6 and 7.

Oppositely spaced about the two inner flanges 17 there are provided two relatively large openings or ports 54 in said inner flange. These ports accordingly establish a free communication from the separating zone 52 between the two flanges 17 and the space within the inner flange and so directly over the funnel 18. Through these ports there is intended to pass the light or waste material that has been held by its lightness upon or close to the surface of the liquid following its deposit by the preceding delivery chute 14 upon the liquid. In order, however, to have a positive gathering of all of this light or waste material that has come from the preceding chute, the skimmer 53 is provided so as to catch and inwardly deflect all of the said light floating material and also a considerable portion of the liquid carrying the same from the separating zone into the space over the funnel 18. Each skimmer consists of a fan-shaped bottom 55. The curved inner edge of this bottom is secured to the inner flange 17 at the bottom edge of the port 54. At the rear edge of the skimmer, that is the edge farthest away from the preceding delivery chute 14, the skimmer has an upstanding back 56 extending from the rear edge of the port upon the inner flange outwardly to the outer flange 16. The back 56 of the skimmer 53 and accordingly the rear edge of the bottom 55 of the skimmer slants or curves forwardly in the direction of rotation of these parts as said back 56 extends away from the inner partition 17 and finally reaches the outer partition 16. This slanting or curved shape of the back operates to gradually deflect towards the port 54 in the inner flange 17 an upper relatively thin or shallow layer of liquid together with the light waste material floating in said layer of liquid in the separating zone 52. It will be understood that the already mentioned vertical adjustment of the shaft 42, which carries suspended therefrom the hub 43, rotating arms 50

and the inner and outer flanges 16 and 17 and the skimmers 53, has for one of its main purposes the vertical adjustment of the skimmers 53 relative to the liquid level 24 in the separating zone 52. The skimmers should be set far enough down into the liquid so as to skim off from the separating zone all of the light floating material and also so as to deflect into the funnel 18 with said light floating material the proper amount of liquid to flow off such light material.

For the purpose of more definitely describing the machine and its operation but without being limited to the precise proportions of liquid supplied at the different parts of the machine or taken from the machine at different parts, it may be said that a satisfactory and efficient arrangement and adjustment of the machine is to have about one-half of the total liquid used by the machine fed into the hopper 15 with the incoming materials to be sorted as by fixing the size of pipe 57 and properly setting the valve 58 on said pipe 57 leading from the pump 39 into the bin 60. Into this bin is placed the material either from suitable receptacles or by a more or less continuous feeding from a conveyor or the like. From the lower part of this bin there extends out over the machine the downwardly directed spout 61 leading the incoming material and one-half of the total liquid to be used. Some portion of the circular hopper 15 is always beneath the outlet spout 61 but as the machine is operated the outwardly extending chutes 14 travel more or less slowly in an anticlockwise direction as the parts are seen in Fig. 2 around the separating zone 52. Each chute 14 deposits its thin layer of material and liquid in a widely spread line over the whole width of the annular or ring-like zone 52 and this line of incoming material and liquid constantly advances about the zone 52. After the material to be separated is thus deposited upon the top of the separating zone, the good material being heavier than the light waste material gradually but relatively quickly settles down through the liquid in the separating zone and passes into the narrowing space between the inner and outer tanks and then into the restricted passageway 34 and continues on to the bottom outlet 21 in said main tank. Meanwhile the light or waste material remains floating in the liquid more or less near the upper level of said liquid and is thus reached and skimmed off from the top of the separating zone by the skimmer 53 which follows the chute 14 which delivered such light material.

The respective pairs of chutes and skimmers are adjustably located relative to each other circumferentially of the separating zone. This is accomplished by rotating the hopper 15 and its chutes 14 relative to the disk 44 which is fixed upon the shaft 42 and accordingly fixed relative to the hub 43 the arms 50 and the inner and outer flanges 17 and 16 to which flanges are fastened the skimmers 53. Holes 45 already mentioned as provided in a row about the disk 44 are adapted to receive a bolt 62 extending through a part of each chute 14 or through a lug or projection provided at the side of such chute. In practice the chute 14 will be adjusted at such a distance ahead of its skimmer 53 as to allow of the good heavy material sinking below the front edge of the bottom 55 of the skimmer before the skimmer reaches such heavy material but as close thereafter as possible so that the waste light material will not have time enough to become saturated with the liquid in which it is now traveling enough to become so heavy as to sink below 150

the forward edge of the bottom 55 of the skimmer 53. In practice the skimmers 53 will take from the separating zone about as much liquid as is being delivered into the separating zone with the oncoming material. Accordingly where the machine is delivering about half of the total liquid to the hopper 15 the skimmers will divert about half of said total liquid from the zone 52 through the ports 54 and into the wide funnel 18 with the light material. This material will be then flowed off through the spout 31 of said funnel 18 into the outlet pipe 32 which conveys the said light material to the screen 33 which separates the liquid from the light material. The liquid taken from such light material it will be understood, is collected in a suitable vat to be used over again by being conveyed to the pump 39 and thence into the system of liquid pipes supplying the machine as a whole.

So as to quickly handle the good heavy material that has sunk through the separating zone it is desirable to provide more or less of a current to the liquid carrying said heavy material to the outlet 21. On the other hand, this downwardly moving current must not be effective in the separating zone or it would carry down with the good material some of the light waste materials. To accomplish this, I have provided the means for supplying a part of the liquid to the machine at a point below the said separating zone. This is accomplished by the numerous small outlets 35 provided in the upper portion of the water collar 78. From these ports there issues a steady stream of liquid totaling about one quarter of the total liquid supplied to the machine which one quarter is supplied to the said water collar through the pipe 37 going from the pipe system extending from the pump 39. It will be seen that the liquid escaping from these small ports has to pass outwardly between the top 29 and the funnel 18 and then downwardly in the relatively narrow space between the vertical wall 28 of the inner tank and the lower portion of the inner flange 17. This admits such incoming water to the space well below the separating zone and supplies said incoming water in a slight current moving downwardly and so towards the restricted passage 34. The quarter of liquid here introduced mingles with the liquid in the space below the separating zone and establishes a downward current which becomes faster as the space becomes more restricted through approaching the smaller end of the two cone-like portions of the two tanks. The movement of liquid out through said bottom port 21 carrying the good heavy materials is further increased by the injector-like action of the liquid supplied by the pipe 26. The liquid supplied by such pipe amounts to about one quarter of the total liquid used by the machine and through its upwardly directed stream in line with the conduit 23 operates to give more speed to the whole body of liquid carried through said conduit and so quickly and easily carries upwardly the good material which is actually heavier than the liquid carrying such material. This good material is delivered into the screen 25 which in an obvious manner separates the liquid from the material and one-half of the liquid coming into said screen into the vat therebelow and so in line to be taken by the pump 39 and thence used over again in the machine.

One defect in my said previous machine was that the single-chambered hopper did not divide the materials evenly and regularly between the two chutes but allowed the larger part to go to

whichever chute had its hopper end opening closest to the main delivery spout. To overcome this defect I have devised the present construction of a two-chambered hopper with each chamber regularly receiving its even one-half of the total materials and liquid from the spout 61 and with each chamber regularly and positively delivering such separate one-half part of the materials and liquid to its own chute 14. The hopper 15 has two concentric chambers—a circular inner chamber 15^a formed by wall 80 upstanding from the bottom 81 of the hopper and thereabout an outer ring-like or annular chamber 15^b formed by outer wall 82 upstanding from the bottom 81 of the hopper.

The delivery of materials and liquid from the main supply bin 60 is so arranged as to deliver one-half of the materials and liquid to the inner chamber 15^a of the hopper and one-half of the said material and liquid to the outer hopper chamber 15^b. A convenient way of so dividing the feed from the bin is to have the spout 61 therefrom so arranged and adjusted that its outer or delivery end will have one-half of its width over the inner chamber 15^a and the other half over the outer hopper chamber 15^b as more particularly appears in Fig. 7.

The outer hopper chamber 15^b connects by means of the opening 15^c in the outer hopper wall 82 to the inner end of the chute 14 for this outer chamber. The inner chamber 15^a connects by means of opening 15^d in the inner wall 80 with the inner end of the other chute 14. It will be understood of course that the respective openings 15^c and 15^d and the inner ends of the respective chutes are arranged opposite to each other so that the said chutes may be in the main similarly shaped and of similar size and yet have the delivery ends 14^a of said chutes spaced oppositely in the separating zone or one-half of the circumference of the separating zone from the delivery end of one chute to the delivery end of the other chute. The distributing chute taking its feed from the inner chamber 15^a has a tunnel-like extension 14^b extending from the inner wall 80 to the circle of the outer wall 82. The side walls and cover of this tunnel-like extension together with the adjacent portion of the bottom 81 of the hopper form an imperforate connecting tunnel from the inner chamber 15^a through the lower part of the outer chamber 15^b and so prevent any mingling of the materials and liquid at this point. Of course this tunnel extension projects upward from the bottom of the outer chamber 15^b for part of the height of said chamber but the walls 80 and 82 of said outer chamber are high enough to still provide sufficient depth over the top of said tunnel-like extension 14^b to receive and deliver the material and liquid coming from the spout 61 even when the rotation of the parts has brought the said tunnel-like extension directly under the delivery end of the spout 61. The peaked or curved top of such extension permits the flow of said material and liquid in either direction to the deeper parts of the outer chamber and such material and liquid find their way at all times to the opening 15^c leading to the chute of this outer chamber.

Preferably each chute 14 instead of extending outwardly or radially in a straight line from the circle of the outer wall 82 of the hopper curves rearwardly relative to its direction of rotation. As the machine is illustrated, the revolving parts rotate in an anticlockwise direction and accordingly the chutes are turned rearwardly or in an

150

apparent clockwise direction as they extend outwardly. This curving rearwardly gradually deflects the outward current of liquid and material into a circular current by the time the material and liquid being delivered comes to the ends 14^a of the chutes. Further means to prevent the uneven grouping or piling up of the material and liquid at the outer extremity of the delivery ends 14^a and to insure the delivery of the material and liquid in an even, regular and thin layer over the whole width of the separating zone 52 consists of a series of curved deflectors 63, 64 and 65 formed or fixed in the bottom of the chutes and upstanding say about one-half an inch where the liquid and materials are flowing from one inch to an inch and a half deep. These deflectors are located in the lower or outer half or third of the chutes, each beginning one after another at the concave side of the chute and curving inwardly therefrom and towards the inner side of the chute and terminating a short distance back from the outer or rearward end of the chutes as appears particularly in Fig. 7. This arrangement and proportioning of the deflectors lets some of the material and liquid flow over the tops of the deflectors but holds or deflects enough of both liquid and materials back towards the convex or inner side of the chute to result in an even distribution of both liquid and materials as they flow over the delivery end of the chute.

Each chute 14 is conveniently formed as a curved, open-topped box tapering gradually to be larger towards its rear or outer end 14^a where the width of the chute is almost the width of the separating zone.

Referring now more particularly to the details shown in Figs. 4 and 5 it will be seen that projecting downwardly from the bottom rear corners of each of the chutes 14 there are two spaced brackets 71. In each pair of these brackets there is rockingly mounted a shaft 72. From this shaft there extends downwardly and slanting rearwardly a plurality of small closely spaced fingers 73. The materials and the accompanying liquid flowing outwardly and rearwardly through the said chutes, pass rearwardly over said rear ends 14^a and out upon the upper surface of the said series of fingers 73 and the liquid passes downwardly through the spaces between said fingers while the fruit or vegetables or other materials being sorted slide downwardly and rearwardly of said fingers and are gently deposited upon the surface of the liquid. It will be understood that as suggested in Figs. 4 and 5 the said fingers extend somewhat into the liquid and are at a gentle angle relative to the level of the liquid. This prevents any of the materials from being plunged violently into the liquid. The rearward flow of the liquid coming out of the chute helps to slide the materials rearwardly of the fingers 73 at about the same rate of travel that the chute has in a forward direction so that the said material is deposited upon the separating zone without any decided momentum either way. The materials are floated off of the lower ends of the said fingers by the trailing of said fingers slightly in the liquid and partly by the backward motion of the material and liquids upon the upper part of the fingers. Neither the trailing of these fingers 73 in the separating zone nor the constantly oncoming curved skimmer are apt to create a forward current in said separating zone because the skimmer takes away from the zone approximately the same amount of liquid as has been just added before the skimmer by each chute. Any forward

current created by the fingers trailing in the liquid is neutralized by the layer of liquid being delivered rearwardly from the said chutes.

Conveniently the shaft 72 is extended inwardly beyond the inner bracket 71 and is there provided with a radially projecting arm 74, the outer end of which can be set into any one of a series of closely spaced holes 75 provided in a sector-shaped rack 76 having its upper end fastened to the adjacent portion of the rear side 64 of the chute. The free end of this rack may be sprung outwardly enough to disengage it from the arm 74 so as to allow said arm and accordingly the shaft 72 and the fingers 73 to be adjusted so that the fingers 73 will have the right angle relative to the surface of the liquid or may project into the liquid more or less as desired. After said fingers are set to desired position the rack 76 will be allowed to spring back into holding engagement with said arm 74.

What I claim as new and desire to secure by Letters Patent is:

1. In a machine of the type described, the combination of an open-topped, main tank having an outlet at the bottom thereof, a smaller closed tank fixed with the main tank, said tanks being closely spaced at their lower parts to form a restricted passage therebetween leading to said bottom outlet, the upper portions of said tanks being spaced farther apart, two circular, spaced rotatably mounted flanges depending into the upper space between said tanks and forming an annular separating zone, the inner flange having a port therethrough, a distributing chute for feeding the in-coming material and some liquid to the said separating zone, said chute being movably mounted above said tanks with its discharge end extending outwardly and movable slowly with said flanges in a circular path above and substantially coinciding with said zone, the receiving part of said chute being relatively fixed over the middle of said tanks, a funnel secured to the inside of said inner flange at the port thereof and extending to the axis of the inner flange for receiving the light-weight material and some liquid, a conduit extending from the lower end of said funnel out through said tanks and a skimmer located between said flanges and traveling therewith and spaced from the chute and shaped to direct the light floating material and some liquid inwardly to said port in the inner flange.

2. In a machine of the type described, the combination of an open-topped, main tank having an outlet at the bottom thereof, a smaller closed tank fixed within the main tank, said tanks being closely spaced at their lower parts to form a restricted passage therebetween leading to said bottom outlet, the upper portions of said tanks being spaced farther apart, two circular, spaced rotatably mounted flanges depending into the upper space between said two tanks and forming an annular separating zone, the inner flange having a port therethrough, a distributing chute for feeding the in-coming material and some liquid to the said separating zone, said chute being movably mounted above said tanks with its discharge end extending outwardly and movable slowly with said flanges in a circular path above and substantially coinciding with said zone, the receiving part of said chute being relatively fixed over the middle of said tanks, a funnel secured to the inside of said inner flange at the port thereof and extending to the axis of the inner flange for receiving the light-weight material and some liquid, a conduit extending from the lower end of said funnel out

through said tanks and a skimmer located between said flanges and traveling therewith and adjustably spaced from the chute and shaped to direct the light floating material and some liquid 5 inwardly to said port in the inner flange.

3. In a machine of the type described, the combination of an open-topped, main tank having an outlet at the bottom thereof, a smaller closed tank fixed within the main tank, said tanks being 10 closely spaced at their lower parts to form a restricted passage therebetween leading to said bottom outlet, the upper portions of said tanks being spaced farther apart, two circular, spaced flanges depending into the upper space between said two 15 tanks and forming an annular separating zone, the inner flange having a port therethrough, a distributing chute for feeding the in-coming material and some liquid to the said separating zone, said chute being movably mounted above said 20 tanks with its discharge end extending outwardly and movable slowly in a circular path above and substantially coinciding with said zone, the receiving part of said chute being relatively fixed over the middle of said tanks, a funnel secured to 25 the inside of said inner flange at the port thereof and extending to the axis of the inner flange for receiving the light-weight material and some liquid, a conduit extending from the lower end of said funnel out through said tanks, a skimmer located 30 between said flanges and spaced from the chute and shaped to direct the light floating material and some liquid inwardly to said port in the inner flange and means to suspend and rotate in unison said flanges, distributing chute and skimmer over said tanks and about a common vertical axis.

4. In a machine of the type described, the combination of an open-topped, main tank having an outlet at the bottom thereof, a smaller closed tank 40 fixed within the main tank, said tanks being closely spaced at their lower parts to form a restricted passage therebetween leading to said bottom outlet, the upper portions of said tanks being spaced farther apart, two circular, spaced flanges 45 depending into the upper space between said two tanks and forming an annular separating zone, the inner flange having a port therethrough, a distributing chute for feeding the in-coming material and some liquid to the said separating zone, 50 said chute being movably mounted above said tanks with its discharge end extending outwardly and movable slowly in a circular path above and substantially coinciding with said zone, the receiving part of said chute being relatively fixed 55 over the middle of said tanks, a funnel secured to the inside of said inner flange at the port thereof and extending to the axis of the inner flange for receiving the light-weight material and some liquid, a conduit extending from the lower end of said funnel 60 out through said tanks, a skimmer located between said flanges and traveling therewith and spaced from the chute and shaped to direct the light floating material and some liquid inwardly to said 65 port in the inner flange and a conduit connected to said bottom outlet of the main tank and leading upwardly with an outlet below the liquid level in the separating zone.

5. In a machine of the type described, the combination of an open-topped, main tank having an 70 outlet at the bottom thereof, a smaller closed tank fixed within the main tank, said tanks being closely spaced at their lower parts to form a restricted passage therebetween leading to said bottom outlet, the upper portions of said tanks being spaced farther apart, two circular, spaced ro- 75

tatably mounted flanges depending into the upper space between said two tanks and forming an annular separating zone, the inner flange having a port therethrough, a distributing chute for feeding the in-coming material and some liquid to the said separating zone, said chute being movably mounted above said tanks with its discharge end extending outwardly and movable slowly with said flanges in a circular path above and substantially coinciding with said zone, the receiving part of said chute being relatively fixed over the middle of said tanks, a funnel secured to the inside of said inner flange at the port thereof and extending to the axis of the inner flange for receiving the light-weight material and some liquid, a conduit extending from the lower end of said funnel out through said tanks, a skimmer located between said flanges and traveling therewith and spaced from the chute and shaped to direct the light floating material and some liquid inwardly to said port in the inner flange and means for adjusting said skimmer vertically. 80

6. In a machine of the type described, the combination of an open-topped, main tank having an outlet at the bottom thereof, a small closed tank 100 fixed within the main tank, said tanks being closely spaced at their lower parts to form a restricted passage therebetween leading to said bottom outlet, the upper portions of said tanks being spaced farther apart, two circular, spaced rotatably 105 mounted flanges depending into the upper space between said two tanks and forming an annular separating zone, the inner flange having a port therethrough, a distributing chute for feeding the in-coming material and some liquid to the said 110 separating zone, said chute being movably mounted above said tanks with its discharge end extending outwardly and movable slowly with said flanges in a circular path above and substantially coinciding with said zone, the receiving part of 115 said chute being relatively fixed over the middle of said tanks, a funnel secured to the inside of said inner flange at the port thereof and extending to the axis of the inner flange for receiving the light-weight material and some liquid, a conduit extending from the lower end of said funnel 120 out through said tanks, a skimmer located between said flanges and traveling therewith and spaced from the chute and shaped to direct the light floating material and some liquid inwardly to said 125 port in the inner flange and a conduit connected to said bottom outlet of the main tank and leading upwardly with an outlet below the liquid level in the separating zone.

7. In a machine of the type described, the combination of an open-topped, main tank having an outlet at the bottom thereof, a smaller closed tank 130 fixed within the main tank, said tanks being closely spaced at their lower parts to form a restricted passage therebetween leading to said 135 bottom outlet, the upper portions of said tanks being spaced farther apart, two circular, spaced rotatably mounted flanges depending into the upper space between said two tanks and forming an annular separating zone, the inner flange 140 having a port therethrough, a distributing chute for feeding the in-coming material and some liquid to the said separating zone, said chute being movably mounted above said tanks with its discharge end extending outwardly and movable 145 slowly with said flanges in a circular path above and substantially coinciding with said zone, the receiving part of said chute being relatively fixed over the middle of said tanks, a funnel secured to the inside of said inner flange at the port there- 150

- of and extending to the axis of the inner flange for receiving the light-weight material and some liquid, a conduit extending from the lower end of said funnel out through said tanks, a skimmer located between said flanges and traveling therewith and spaced from the chute and shaped to direct the light floating material and some liquid inwardly to said port in the inner flange, a conduit connected to said bottom outlet of the main tank and leading upwardly with an outlet below the liquid level in the separating zone and means to supply liquid under pressure to said conduit in an upward direction to induce flow outwardly through the bottom outlet of the main tank.
8. In a machine of the type described, the combination of an open-topped, main tank having an outlet at the bottom thereof, a smaller closed tank fixed within the main tank, said tanks being closely spaced at their lower parts to form a restricted passage therebetween leading to said bottom outlet, the upper portions of said tanks being spaced farther apart, two circular, spaced, rotatably mounted flanges depending into the upper space between said two tanks and forming an annular separating zone, the inner flange having a port therethrough, means to supply liquid to flow out beneath said inner flange into the space below said separating zone, a distributing chute for feeding the in-coming material and some liquid to the said separating zone, said chute being movably mounted above said tanks with its discharge end extending outwardly and movable slowly with said flanges in a circular path above and substantially coinciding with said zone, the receiving part of said chute being relatively fixed over the middle of said tanks, a funnel secured to the inside of said inner flange at the port thereof and extending to the axis of the inner flange for receiving the light-weight material and some liquid, a conduit extending from the lower end of said funnel out through said tanks and a skimmer located between said flanges and traveling therewith and spaced from the chute and shaped to direct the light floating material and some liquid inwardly to said port in the inner flange.
9. In a machine of the type described, the combination of an annular deep open-topped trough having an outlet at its bottom, two circular spaced rotatably mounted flanges depending into the upper portion of said trough and forming an annular separating zone, the inner flange having ports therethrough, a hopper rotatably mounted above said trough and flanges on the axis of said flanges, distributing chutes extending outwardly from said hopper to said separating zone, liquid-conducting means secured to the said inner flange at the ports thereof, skimmers located between said flanges and traveling therewith and spaced from the preceding chute and shaped to direct material and liquid inwardly to the ports in the inner flange.
10. In a machine of the type described the combination of an annular open-topped trough forming a separating zone in its upper portion and having an outlet therebelow, a hopper rotatably mounted above the trough on the axis of said trough, distributing chutes extending from said hopper to said separating zone, said chutes revolving with said hopper and curving rearwardly relative to the direction of their movement as they extend outwardly and spaced deflectors standing from the bottom of the outer and rearward portion of said chutes and beginning at the concave side of said chutes and curving away from said concave side as the deflectors extend towards the delivery end of the chutes.
